UNITED STATES PATENT OFFICE.

HAROLD A. R. PRINDLE AND JOHN U. ADOLPH, OF PHILADELPHIA,
PENNSYLVANIA.

PNEUMATIC TOOL.

No. 839,031.

Specification of Letters Patent.

Patented Dec. 18, 1906.

Application filed October 10, 1904. Serial No. 227,896.

To all whom it may concern:

Be it known that we, HAROLD A. R. PRINDLE and JOHN U. ADOLPH, of Philadelphia, in the county of Philadelphia and State of Pennsylvania, have invented a certain new and useful Improvement in Pneumatic Tools; and we do hereby declare that the following is a full, clear, and exact description thereof, reference being had to the accompanying drawings, in which—

Figures 1 and 2 are longitudinal sectional views of a tool embodying our invention, showing the parts in different positions; and

Figs. 3, 4, and 5 are respectively sectional views taken on the lines 3 3, 4 4, and 5 5 of Fig. 2.

The object of our invention has been to provide a pneumatic tool in which there shall be a free exhaust during the entire down or working stroke of the hammer, and such exhaust on the return stroke, except as it is to cushion the hammer; in which the valve shall be held both up and down by live air, so that leakage cannot disturb its position; in which the valve shall be strong and not easily broken, and in which a very rapid stroke is possible, because the valve is actuated in both directions by live air; and to such ends our invention consists in the pneumatic tool hereinafter specified.

In carrying our invention into practice we provide a shell A, provided with a bore B, in which is mounted a hammer C, the hammer being preferably in the form of a plain cylinder. A tool D is mounted in the lower end of the shell A in any desired manner. In the form which we have illustrated the tool D is provided with an end or shank d, that fits a passage e in the shell A, such passage permitting the shank to extend up where it can be struck by the hammer. A collar e' on the tool-shank properly positions the tool. A cap F is screwed on the lower end of the shell and compresses a spring G, that surrounds the tool, against the said collar and tends to hold the tool up in position to receive a blow from the hammer. Upon the upper end of the shell A a handle H is mounted in any desired manner. As we have illustrated it the shell is provided with an external thread, and the part H is screwed upon said thread. A disk I is seated upon the upper end of the shell, dowel-pins being

provided to prevent the turning of the disk with reference to the shell, and upon said disk a valve-casing K is mounted, the said casing being provided with a bore k of larger diameter at its lower end and a bore k' of smaller diameter extending through to its opposite end. The handle H is provided with an interior surface h, that bears upon the valve-casing and forces the disk against the shell. The handle is provided with an air-passage h', which is governed by a balanced valve L, the latter being in the form of a plug sliding in a passage h² in the handle. The plug is normally raised by a spring M, seated beneath it in the passage h², and such plug extends up into convenient reach of the thumb of the operator. The plug is provided with a neck or groove l normally above the passage h'. A passage h⁴ beside the passage h' communicates with the neck l when the latter is at the level of the passage h'. By shifting the valve so that its neck is opposite the air-passages air can pass through the said passages to reach the valve-casing. When the valve is raised so that its neck is not coincident with the passages, the flow of air is prevented.

Within the valve-casing is mounted a valve N, having a larger cylindrical portion n, that fits the larger and lower bore k in the valve-casing and that is provided with an annular groove n' in its periphery, which latter in the upper position of the valve is adapted to communicate with a passage O, formed in the valve-casing, the said passage O extending down to the bottom of the central or piston bore B of the shell A to permit air to reach the under side of the hammer. The groove n' connects by a hole or holes with a central passage n² in the valve, which passage extends through the valve to its upper end, so that live air can enter. The valve is provided with a stem n³, which fits the smaller bore k' in the valve-casing, the said stem being provided with a neck or groove n⁴, which is adapted to act like a D-valve in connection with upper and lower passages P and Q. The lower passage Q communicates with the outer air through the passage q, while the upper passage P communicates by the passage p with the upper end of the central bore of the shell A to permit the air to reach the upper side of the piston. A preferably small pas-

sage R affords communication between the live-air passage h^4 and the lower portion of the bore k , the exit of such passage being at such level that the portion n^5 of the face of the piston covers such exit in the lowest position of the valve. A passage S extends from the upper face of the disk I to a point in the bore B just above the piston in its lowest position. An exhaust-passage T extends from a point in the lower part of the bore B to an exit to the outer air at any desired point. A passage U connects the upper end of the larger bore k with the outer air.

In the operation of the above-illustrated hammer, the parts being assumed to be in the position illustrated in Fig. 1, live air is admitted to the passage h^4 by depressing the valve L, as by means of the thumb, and such air, by means of the passages P and p , reaches the upper side of the hammer and forces the latter down upon the tool, the air in advance of the hammer exhausting through the passage T and (after the hammer has passed the entrance to such passage) exhausting through the passages O and U to the outer air. It will be seen that we provide a free exhaust for the air through the working stroke of the hammer and that no force is lost by cushioning. When the piston passes the entrance to the passage S, the live air enters such passage and, reaching the under side of the valve in the bore k , raises the valve to the position illustrated in Fig. 2, in which position the valve has uncovered the passage R, thus permitting live air to pass from the passage h^4 directly beneath the valve. The valve is thus sustained in its upper position (as well as in its lower position) by live air, and leakage cannot cause it to be displaced. The raising of the valve to its upper position causes the groove n to coincide with the passage O, and live air can thus pass through the bore n^5 in the valve-stem, through the holes n' in the larger portion N of the valve, and through the groove and passage O to the bottom of the bore B and beneath the hammer, such air suddenly raising the hammer until the entrance to the passage T in the bore is uncovered, when the air will exhaust through such passage. While the hammer is rising, the air above it exhausts through the passages p and P into the neck n^4 of the valve-stem and thence through the passages Q and q to the outer air. As the hammer passes above the entrance in the bore of the passage S it permits the air beneath the valve to exhaust through such passage and the passage T until the valve is forced down by the live-air pressure on its upper end, (the passage S being larger than the passage R, causing an exhaust more rapidly than the passage R can supply.) The valve reaches the position illustrated in Fig. 1 in time to cause any cushioning that may be desired on the return stroke of the hammer by closing the passage P and pre-

venting further exhaust of the air above the piston. The cycle of operations above described is then repeated.

It will be observed that our hammer has the following advantages: There is no back pressure retarding the hammer during its working stroke, and as little cushioning as is desired can be provided on the return stroke. The valve is simple and strong and is held in both positions by live air, so that leakage cannot disturb its position. The valve is moved in both directions entirely by live air. These advantages cause the action of our tool to be extremely rapid.

It is obvious that changes can be made in the above-illustrated construction that will be within the scope of our invention. We desire not to be limited beyond the requirements of the prior art and the terms of our claims.

Having thus described our invention, what we claim is—

1. In a pneumatic tool, the combination of a casing having a bore for a hammer, a hammer, a valve, such tool having a live-air passage that is uncovered by the movement of the valve next following the working stroke of the hammer, the air from such passage serving to maintain the valve in the position then assumed and said passage being independent of those for supplying air to the hammer.

2. In a pneumatic tool, the combination of a casing having a bore for a hammer, a hammer in such bore, a valve, a passage communicating with the under side of the valve and adapted to be uncovered by the hammer as it reaches the end of its working stroke, and a live-air passage adapted to be uncovered by the valve during the movement thereof caused by the air from the passage first mentioned said live-air passage being independent of those for supplying air to the hammer.

3. In a pneumatic tool, the combination of a valve having larger and smaller cylindrical portions and having a neck formed in such smaller portion, said larger portion having a groove in its periphery that communicates with a bore in its stem, and a valve-casing having exhaust and supply ports that are adapted to be disconnected and connected by said smaller cylindrical portion of the valve and said neck, respectively, and an exhaust and supply port that is adapted to be supplied through said groove, and exhausted by being uncovered by said larger cylindrical portion of the valve.

4. In a pneumatic tool, the combination of a valve having larger and smaller cylindrical portions and having a neck formed in such smaller portion, said larger portion having a groove in its periphery that communicates with a bore in its stem, and a valve-casing having exhaust and supply ports that are

adapted to be disconnected and connected by said smaller cylindrical portion of the valve and said neck, respectively, and an exhaust and supply port that is adapted to be supplied through said groove, and exhausted by being uncovered by said larger cylindrical portion of the valve, and a live-air passage adapted to be covered by said larger cylindrical portion of the valve, in the lowest position of the valve.

5. In a pneumatic tool, the combination of a casing having a bore for a hammer, a hammer, a valve consisting of a stem having a neck and a cylindrical head, a casing in which said valve is adapted to reciprocate, a supply-port for the upper end of said bore, and an exhaust-port therefor, that are adapted to be put in communication by said neck, or closed by said stem, and a supply and exhaust port for the lower end of said bore that is adapted to be supplied by a passage through said stem and head and to be exhausted by being uncovered by said head the exhaust being kept open throughout the 25 working stroke of the hammer.

6. In a pneumatic tool, the combination of a casing having a bore for a hammer, a hammer, a valve consisting of a stem having a neck and a cylindrical head, a casing in which said valve is adapted to reciprocate, a supply-port for the upper end of said bore, and an exhaust-port therefor, that are adapted to be put in communication by said neck, or closed by said stem, a supply and exhaust port for the lower end of said bore that is adapted to be supplied by a passage through

said stem and head and to be exhausted by being uncovered by said head, the exhaust being kept open throughout the working stroke of the hammer and a passage adapted 40 to be uncovered by said hammer on its working stroke and communicating with the head end of said valve-casing.

7. In a pneumatic tool, the combination of a casing having a bore for a hammer, a hammer, a valve consisting of a stem having a neck and a cylindrical head, a casing in which said valve is adapted to reciprocate, a supply-port for the upper end of said bore, and an exhaust-port therefor, that are adapted 45 to be put in communication by said neck, or closed by said stem, a supply and exhaust port for the lower end of said bore that is adapted to be supplied by a passage through said stem and head and to be exhausted by 50 being uncovered by said head, a passage adapted to be uncovered by said hammer on its working stroke and communicating with the head end of said valve-casing to supply air to shift the valve, and a live-air passage 55 adapted to be covered by said head in the lowest position of the valve that supplies air to the valve to maintain the same in the position to which it is shifted.

In testimony that we claim the foregoing 65 we have hereunto set our hands.

HAROLD A. R. PRINDLE.
JOHN U. ADOLPH.
